UNITED STATES PATENT OFFICE.

LYMAN R. ROBERTS, OF RUTHERFORD, NEW JERSEY, ASSIGNOR TO L. R. ROBERTS
TYPEWRITER COMPANY, OF STAMFORD, CONNECTICUT, A CORPORATION OF
DELAWARE.

TYPEWRITER.

Application filed August 3, 1920. Serial No. 400,891.

To all whom it may concern:

Be it known that I, LYMAN R. ROBERTS, a citizen of the United States, residing at Rutherford, county of Bergen, and State of New Jersey, have invented certain new and useful Improvements in Typewriters, fully described and represented in the following specification and the accompanying drawings, forming a part of the same.

10 This invention relates to improvements in typewriters.

In the use of typewriters, as heretofore known, trouble has been caused by the loss of proper alignment, due to the bouncing or 15 quivering of the case-shifting parts.

It is the principal object of the present invention to provide a typewriter so constructed that bouncing or quivering of the case-shifting parts is prevented whether these 20 parts are in normal or shifted position.

With this general object in view, the invention consists in the combinations, details of construction and arrangements of parts which will first be described in connection 25 with the accompanying drawings and then more particularly pointed out.

In the drawings:

Figure 1 is a view, in vertical section, of so much of a typewriter, constructed in accordance with the invention, as is necessary to an understanding thereof;

Figure 2 is a view of the same, with parts removed, in rear elevation;

Figure 3 is a transverse sectional view 35 taken through the case shift levers;

Figure 4 is a view similar to Fig. 1, with parts removed, showing the parts in intermediate case shift position;

Figure 5 is a similar view showing the 40 parts in extreme case shift position;

Figure 6 is a cross-sectional view taken on the line 6 of Fig. 5;

Figure 7 is a view similar to Fig. 3 showing a different position of the parts; and

Figure 8 is a face view of the spacing member removed.

Referring to the drawings, typewriters constructed in accordance with the invention include a case shifting unit. The typewriter herein illustrated as an example is of the class in which the platen is case-shifted, but it is to be understood that the invention is applicable also to typewriters having case-shifting type units.

In typewriters embodying a case-shifting platen unit, this unit may comprise various elements depending on the construction of the machine as a whole. In the present embodiment the case shifting unit includes a platen 11, a platen carriage 12 in which the platen shaft is journaled, a carriage truck 13 on which the carriage is mounted for printing movement, vertically sliding plungers 14 on which the carriage truck is rigidly mounted, and a lifting rod 15 connecting the plungers by passing through suitable holes therein.

The above named elements make up a rigidly connected unit, that is bodily movable from one case position to another, the plungers 14 sliding in stationary bearing portions 16 of the frame 17.

Means is provided for case shifting this platen unit into either of two positions for writing upper case letters and figures, and in the present construction the platen unit is raised from normal position either to an intermediate or extreme vertical position. In structures embodying the invention to the best advantage, the lifting rod 15 is raised by a lever having an operating connection with one or more case-shift key levers forming part of the key-board of the machine, the movement being limited by the engagement of the lifting rod with a relatively stationary stop or abutment. Although capable of various constructions, in that here illustrated, mounted on a rock shaft 18 is a lifting lever 19, the free end of which extends beneath the lifting rod 15. Also mounted on the rock shaft is a rocking lever 20, depression of which rocks the shaft 18 and thus swings lever 19 upwardly against the lifting rod 15 to raise the platen unit.

Forming part of the key-board of the machine are the case shift key levers 22, 23, for intermediate and extreme case shift. The lever 22 has a lug 24 extending over the rocking lever 18, and key lever 23 has a lug 25 also extending over the rocking lever. Upon operation of either key lever its respective lug forces down the rocking lever 18 with the result above described.

Means is provided for limiting the upward movement of the platen unit, and in structures embodying the invention to the best advantage a relatively stationary stop

or abutment is provided for engagement by part of the platen unit, for example, by the lifting rod. In the present exemplification, for extreme case shift the movement of the platen unit is limited by the engagement of the lifting rod 15 with a stop or abutment in the form of an adjustable wedge 28 mounted on the bottom of the frame bearing portions 16. To provide a different limit for intermediate case shift, a spacing lug is inserted between the wedge 28 and the lifting rod to serve as a limiting stop.

In the construction here shown as an example, the intermediate case shift lever 22 has an arm 30 carrying a pin 31 which rides in a slot 32 formed in a movable plate 33. This plate is also slotted at 34 and rides on two aligned pins 35. At its rear end, the plate 33 has a spacing lug 36. Upon operation of the intermediate case shift lever, the pin 31 moves the plate rearwardly to interpose the spacing lug 36 between the wedge 28 and the lifting rod 15.

The invention includes means for locking the case shift levers in operated position for writing all "caps" or all "figs." Although this locking means may vary in construction, in the form shown, pivoted on the key lever comb piece 38 is a shift locking lever 39 having an operating key or handle 40. This locking lever has two legs 41, 42, the feet of which are arranged to extend above the respective case shift levers 22, 23. Fig. 3 shows the parts in normal position. When case shift lever 23 is operated and is to be locked for continuous figure printing, the locking lever 39 is swung on its pivot so that leg 42 moves into a position above the depressed case shift lever and holds the latter down. Leg 41 is so formed as to pass around the normally positioned case shift lever 22 in this position of the parts, which is shown in Fig. 7. It will be apparent that when the other case shift lever 22 is operated, a like movement of the locking lever holds down the case shift lever by means of the other leg 41, while leg 42 passes around the normally positioned case shift lever 23.

To return the locking lever 39 to its normal neutral position a spring 43 connects the lever and the comb plate 38. When it is desired to release the platen from case shifted position, a slight further depression of the case shift lever relieves the tension on the locking leg and the spring 43 moves the locking lever 39 back to neutral position.

To prevent bouncing and quivering of the case shifting unit, the invention includes means for rigidly holding the unit against shifting movement. This may be accomplished, for example, by providing a relatively stationary anchor and means movable into a position to hold the unit spaced from such anchor. In structures embodying the invention to the best advantage, there is pro-

vided a combined spacing member that is tied to an anchor located below the shifting platen unit. One part of this spacing member is designed to hook over a part of the platen unit when in normal position to hold the same down. The other part of the spacing member is designed to move in between a part of the case-shift platen unit and the anchor, to hold the unit spaced therefrom.

Although capable of various constructions, in the embodiment here illustrated as an example, a relatively stationary anchor is provided in the form of a rock shaft 45 journaled in the frame 17 and extending across the machine beneath the lifting rod 15. Mounted on this rock shaft near one end is a combination spacing member indicated generally by 46 and hereinafter described in detail. This spacing member is secured to the rock shaft in any suitable manner, as by the collar 47 and screw 48. The spacing member is a metal plate extending upwardly from the rock shaft and is roughly Y-shaped, as appears more clearly in Fig. 8. It comprises a normal spacing arm 49 and a shift spacing arm 50. The normal spacing arm 49 is notched at 51 and the parts are so arranged that when the platen unit is in its normal position the notch 51 takes over the lifting rod 15 which nests in the crotch of the Y. The platen unit is thus rigidly held down to the anchor and bouncing and quivering in normal position is avoided. This normal spacing member is removed to permit case shift by means hereinafter described.

To rigidly hold the platen unit in intermediate shifted position the shift spacing arm 50 is formed with a shoulder 52 designed to take under the lifting rod 15, when the platen unit is shifted to intermediate position. Thus there is interposed a rigid part between the shifted platen unit and the stationary anchor, which in connection with the shifting limiting stop elements before described, holds the platen unit against bouncing and quivering.

A like result is obtained for extreme case shift by means of the end of the arm 50. The arm is so arranged that when the platen unit is shifted to extreme position the end of arm 50 can take under lifting rod 15 whereby the platen unit is rigidly held in position as above described. A projection 53 on the end of arm 50 serves to limit the movement of the spacing member by engaging lifting rod 15 (see Fig. 5). To accommodate the rod 15 when the platen is in intermediate position, the arm 50 is cut away or notched as at 54.

To normally hold the normal spacing member 49 in spacing position, there is provided, in the present exemplification, a spring 55 connected between the tail piece of the

Y-shaped plate 46 and a pin 56 on the frame. Means is provided for removing the normal spacing member to permit case shift and for moving the shift spacing member 5 into spacing position. In embodiments of the invention in which the two spacing elements are moved simultaneously as in the case of the construction described, these two ends may be conveniently accomplished by 10 the same means, for example, means to rock the shaft 45.

In structures embodying the invention to the best advantage, means for removing the normal spacer and for inserting the shift 15 spacer are brought into operation upon operation of either case shift key lever.

Although capable of various constructions, in that here illustrated, as an example, the shaft 45 is rocked upon operation 20 of either case shift lever, by means of a rocking arm 57 secured to the shaft 45. This rocker arm is engaged by a pin 58 on the shifting lever 19. The rocker arm is notched, as shown, and in normal position 25 of the parts (Fig. 1) the pin 58 seats in such notch. Upon operation of a case shift lever, the consequent movement of lifting lever 19 causes the pin 58, riding up the edge of the rocker arm 57, to rock shaft 45. This 30 movement of the shaft removes the normal spacing member 49 to permit case shift movement and in the same operation inserts the shaft spacing member in spacing position.

The invention includes means for locking 35 the shift spacing member in spacing position and in structures embodying the invention to the best advantage this locking means is brought into operation upon operation of the case shift lever lock. This 40 may be accomplished, for example, by clamping the spacing member into position with a cam action. Although capable of various constructions, in that here illustrated, pivoted to the locking lever 39 which locks 45 the case shift lever, is one end of a bell crank 60, the other end being pivoted to a crank arm 61 formed on a rod 62. This rod extends to the rear of the machine and is journaled in bearing members 63. At its rear 50 end the rod 62 is bent downwardly to form a pusher 64. Upon operation of the locking lever 39, through the bell crank 60 and the crank 61, the rod 62 is oscillated to swing the pusher 64. To receive the action of the 55 pusher the spacing member is provided with an inclined lug 65. The movement of the pusher against this inclined lug cams the spacing member firmly into spacing position and locks it therein. It will be clear that 60 the spacing member is released from this locking action upon release of the case-shift lever lock. As the locking lever 39 returns to normal position, as above described, the pusher 64, by bell-crank 60, crank 61 and 65 rod 62, is moved away from the cam lug 65.

In typewriters embodying the invention to the best advantage, spacing members are provided at each side of the machine. In the present embodiment, 66 represents generally a combination spacing member that 70 is a duplicate of the one described, except that it has no cam lug 65.

The operation of the parts described will be clear from the foregoing without further 75 description.

What is claimed is:

1. In a typewriter, and in combination, a frame, a case-shift unit movable in the frame, a lifting lever for case-shifting said unit, a rock shaft journaled in the frame, a 80 combined locking member mounted on said rock shaft and having an arm for hooking over a portion of said unit to prevent movement thereof out of normal position and a second arm, normally out of operative position, for taking under a portion of said unit when in shifted position to hold the same in such position; a rocker arm on said rock shaft, and a pin on said lifting lever for engaging said rocker arm to rock said shaft, 85 thereby to remove said first named arm out of locking position and to insert said second arm into operative position.

2. In a typewriter, and in combination, a frame, a case-shift unit movable in the 90 frame and including a cross bar, a lifting lever for engaging said cross bar to case-shift said unit, a rock shaft journaled in the frame, a combined locking member mounted on said rock shaft and having an 100 arm for hooking over said cross rod to prevent movement of the unit out of normal position and a second arm, normally out of operative position and movable to a position beneath said cross rod when in shifted position, to hold the unit in said position, a rocker arm on said rock shaft, and a pin on said lifting lever for engaging said rocker arm to rock said shaft, thereby to remove 105 said first named arm out of locking position and to insert said second arm into operative position.

3. In a typewriter, and in combination, a frame, a case-shift unit movable in the frame, means, including a plurality of case-shift key levers, for shifting said unit into intermediate and extreme case-shift positions, a combined locking member pivotally anchored to the frame and having an arm normally hooking over a portion of said 115 unit to hold the unit against movement out of normal position and a second arm, normally out of operative position, and having two shoulders, one for taking under a portion of the unit when in intermediate shifted position, the other for taking under a portion of the unit when in extreme shifted position, thereby to hold the unit in such 120 positions, and means, operable upon operation of either of said key levers, for swing- 130

ing said locking member to remove said first named arm out of locking position and to insert said second arm in operative position.

4. In a typewriter, and in combination, a frame, a case-shift unit movable in the frame, a lifting lever for case-shifting said unit, a combined locking member pivotally anchored to the frame and having an arm normally hooking over a portion of said unit to prevent movement thereof out of normal position and a second arm, normally out of operative position, for taking under a portion of said unit when in shifted position to hold the same in such position, means, operable upon operation of said lifting lever, for swinging said locking member to remove said first named arm from locking position and insert said second arm in operable position, and means acting directly on said locking member for holding said second arm in operable position.

5. In a typewriter, and in combination, a frame, a case-shift unit movable in the frame, means, including a case-shift lever, for case-shifting said unit, a locking device movable to lock said lever in operated position, a combined locking member pivotally anchored to the frame and having an arm normally hooking over a portion of said unit to prevent movement thereof out of normal position and a second arm, normally out of operative position, for taking under a portion of said unit when in shifted position to hold the same in such position, means, operable upon operation of said lever, for swinging said locking member to remove said first named arm from locking position and insert said second arm into operative position, and means, operable upon operation of said lever locking device, for acting directly on said locking member to hold said second arm in operative position.

6. In a typewriter, and in combination, a frame, a case-shifting unit, means including a key lever for case-shifting said unit, means for locking said key lever in operated position, a rock shaft journaled in the frame, a spacing member secured to said rock shaft and movable into a position to hold said unit spaced from the rock shaft, means operating upon operation of said key lever for rocking said shaft to move said spacing member into spacing position, and means operating upon operation of said key lever locking means for imposing a cam action directly on said spacing member to lock the latter in spacing position.

7. In a typewriter, and in combination, a case shifting unit, means including a key

lever for case shifting said unit, means for locking said key lever in operated position, an anchor abutment, a spacing member movable into a position to hold said unit spaced from said anchor, means operating upon operation of said key lever for moving said spacing member into spacing position, an inclined lug on said spacing member, a pusher for acting on said lug to lock the spacing member in spacing position, and a connection between said pusher and said key lever locking means.

8. In a typewriter, and, in combination, a frame, a case-shift unit movable in the frame, means, including a case-shift lever, for case-shifting said unit, a locking device movable to lock said lever in operated position, a combined locking member pivotally anchored to the frame and having an arm normally hooking over a portion of said unit to prevent movement thereof out of normal position and a second arm normally out of operative position, for taking under a portion of said unit when in shifted position to hold the same in such position, means, operable upon operation of said lever, for swinging said locking member to remove said first named arm from locking position and insert said second arm into operative position, an inclined lug on said locking member, a pusher for acting on said lug to lock the second arm in operative position, and a connection between said pusher and said lever locking device.

9. In a typewriter, and in combination, a frame, a case-shift unit movable in the frame and including a cross bar, a lifting lever for engaging said cross bar to shift the unit into intermediate or extreme case-shift positions, a rock shaft journaled in the frame, a combined locking member mounted on said rock shaft and having an arm normally hooking over said cross rod to prevent movement of the unit out of normal position, and a second arm, normally out of operative position and movable to take locking relation with said cross bar when the unit is in either of said shifted positions, to hold the unit in such position, and a rocker arm on the rock shaft, operable upon operation of said lifting lever to swing the combined locking member, thereby to remove the first named arm out of locking position and to insert the second arm in operative position.

In testimony whereof, I have hereunto set my hand.

LYMAN R. ROBERTS.
